US0D1030065S

(12) **United States Design Patent** (10) **Patent No.:** **US D1,030,065 S**
(45) **Date of Patent:** **** Jun. 4, 2024**

(54) **MEDICAL DEVICE FOR TRICUSPID VALVE REGURGITATION**

(71) Applicant: **TAU CARDIO INC.**, Centreville, VA (US)

(72) Inventor: **June Hong Kim**, Busan (KR)

(73) Assignees: **TAU CARDIO INC.**, Centreville, VA (US); **TAU MEDICAL INC.**, Busan (KR)

(**) Term: **15 Years**

(21) Appl. No.: **29/822,323**

(22) Filed: **Jan. 7, 2022**

CLAIM

The ornamental design for a medical device for tricuspid valve regurgitation, as shown and described.

DESCRIPTION

FIG. 1 is a perspective view of a medical device for tricuspid valve regurgitation;

FIG. 2 is a front view thereof;

FIG. 3 is a rear view thereof;

FIG. 4 is a top view thereof;

FIG. 5 is a bottom view thereof;

FIG. 6 is a left view thereof;

FIG. 7 is a right view thereof;

FIG. 8 is a perspective view of another embodiment having a different design of the proximal member;

FIG. 9 is a left view thereof;

FIG. 10 is a right view thereof; and,

FIG. 11 is a reference view where the device is placed within the heart.

The broken lines depict environmental subject matter that form no part of the claimed design.

1 Claim, 10 Drawing Sheets
